MANIFOLD FOR INTERNAL-COMBUSTION ENGINES

Frederick J. Holmes, St. Clair Shores, Mich.

Application September 27, 1946, Serial No. 699,606

2 Claims. (Cl. 257—241)

16

This invention relates to internal combustion engines, and has for its general object to provide simple, practical means to adapt internal combustion engines of the type which are designed primarily to burn more or less highly refined fuels, such as gasoline, for highly efficient, economical operation by considerably heavier fuels, such as commercial fuel oil.

The invention contemplates employment of the usual engine carburetor to atomize the fuel oil, and in this connection a special and important object of the invention is to provide simple, practical means for utilizing the heat of the engine exhaust gases to heat the fuel oil to a proper temperature for most effective atomization by the carburetor prior to its delivery thereto, and to maintain it at that temperature.

Another special and important object of the invention is to provide simple, practical means for utilizing the heat of the engine exhaust gases to heat the combustion sustaining air that is supplied to the carburetor for intermixture with the atomized oil, and to maintain it at the proper temperature to afford the most efficient fuel mixture.

With the foregoing and other objects in view, which will become more fully apparent as the nature of the invention is better understood, the same consists in the novel combination and arrangement of features as will be hereinafter more fully described, illustrated in the accompanying drawings and defined in the appended claims.

In the accompanying drawings, wherein like characters of reference denote corresponding parts in related views:

Fig. 1 is a side elevation of a portion of an internal combustion engine illustrating a fuel system in accordance with one practical embodiment of the invention applied thereto.

Fig. 2 is a longitudinal section through a portion of the exhaust manifold of the engine.

Fig. 3 is a section on the line 3—3 of Fig. 1.

Fig. 4 is a section on the line 4—4 of Fig. 1.

Fig. 5 is a view similar to Fig. 1 illustrating an alternative embodiment of the invention.

Fig. 6 is a top plan view of the structure illustrated in Fig. 5; and

Fig. 7 is a longitudinal section through the engine manifold of the Figs. 5 and 6 embodiment of the invention.

Referring to the drawings in detail, first with particular reference to the embodiment of the invention illustrated in Figs. 1 to 4 of the drawings, A designates, generally, a portion of an internal combustion engine of a type which is de-

signed primarily for the use of gasoline as fuel and which includes, as usual, an intake manifold 10, an exhaust manifold 11, and a carburetor 12 connected to said intake manifold.

In accordance with the invention, the intake and the exhaust manifolds may be formed either separately from each other or as a one-piece unit. In any event, the exhaust manifold is of special construction in that it is provided, near its outlet end, with a chamber 13 and with a valve 14 for controlling flow of engine exhaust gases therethrough.

Suitably mounted within the chamber 13 is a fuel oil container 15 to which leads an oil supply pipe 16 and from which leads an oil delivery pipe 17 which is connected to the carburetor 12 through a valve 18. Thus, fuel oil delivered to the carburetor is required to pass through said container.

Within the container 15 is a thermostat 19 which may be of any suitable type and which may be connected to the valve 14 in any suitable manner for actuating the latter in response to variations in the temperature of the fuel oil in said container.

In the present instance the thermostat 19 is illustrated as including a plunger 20 which extends through the front wall of the chamber 13 for projection and retraction in response to rise and fall, respectively, of oil in the container 15 above and below a predetermined temperature.

The valve 14 preferably is of the swinging leaf type and the connection between the same and the thermostat 19 is illustrated in the present instance as comprising a bell-crank lever 21 pivoted at 22 to a post 23 carried by the front walls of the chamber 13 and having one of its arms 24 connected by a rod 25 to an arm 26 on the shaft 27 of said valve 14 and its other arm 28 overlying the outer end of the plunger 20.

The arrangement of the bell-crank lever 21 is such that when the plunger 20 is projected it swings said lever in a direction to swing the valve 14 to a position to divert exhaust gases from the chamber 13. On the other hand, a suitable spring 29 tends constantly to swing said lever in the opposite direction, and is effective to do so upon retraction of the plunger 20, to swing the valve 14 to a position to direct exhaust gases through the chamber 13. Since the temperature of the oil in the container 15 controls the position of the valve 14, and since said valve controls the amount of the exhaust gases which flow through the chamber 13 and which serve to heat the oil in said container, it is manifest that the described mecha-

anism may, by proper adjustment, be rendered effective to maintain the oil supplied to the carburetor 12 at a predetermined temperature best suited for use as fuel by the engine.

The invention further includes means for utilizing the exhaust gases of the engine to maintain the air supplied to the carburetor 12 at a predetermined temperature best suiting it for intermixture with the oil to afford a most efficient engine fuel. This means, according to the Figs. 1 to 4 embodiment of the invention, includes a jacket 30 surrounding the engine exhaust pipe 31, whereby air within said jacket is heated by hot exhaust gases flowing through said exhaust pipe.

Connected to the carburetor 12 is an air supply pipe 32 which has two branches 33 and 34, the former of which may be open to the atmosphere or connected to an air filter 35 for supply of air at atmospheric temperature to the pipe 32, and the other of which is connected to the jacket 30 for supply of heated air to said pipe 32.

In the pipes 33 and 34 are suitable valves 36 and 37, respectively, which are suitably coupled together, as indicated at 38, so that opening of one closes the other and vice-versa.

In the pipe 32 is a thermostat 39 which may be of any suitable type and which may be connected in any suitable manner with the valves 36 and 37 for actuating the latter in response to variations in the temperature of the air in said pipe 32.

The thermostat 39 is illustrated as being of the bellows type and as including a plunger 40 which extends exteriorly of the pipe 32 and which is projected and retracted in response to rise and fall, respectively, of the air in the pipe 32 above and below a predetermined temperature. Pivoted at 41 to a suitable fixed support is a bell-crank lever 42 one arm 43 of which is connected to the outer end of the plunger 40 and the other arm 44 of which is connected by a rod 45 with an arm 46 on the shaft 47 of the valve 36, the arrangement in this respect being such that when the plunger 40 is projected it swings said bell-crank lever in a direction to open the valve 36 and close the valve 37. A suitable spring 48 tends constantly to swing said bell-crank lever in the opposite direction and is effective to do so, upon retraction of the plunger 40, to close the valve 36 and open the valve 37.

Since cool air is supplied to the pipe 32 from the pipe 33 and heated air is supplied to said pipe 32 from the pipe 34, and since the thermostat 40 together with the spring 48, controls the valves 36 and 37, it is apparent that by a proper adjustment of the connections between said thermostat and said valves the air in the pipe 32 may be maintained at a temperature best suited for intermixture with the oil to afford a most efficient engine fuel.

The jacket 30 has an air inlet opening which may communicate either directly with the atmosphere or be connected to the air filter 35. In the present instance it is shown as being connected by a pipe 49 to the pipe 33 and hence to the air filter 35.

Connected to the carburetor 12 is a supply pipe 50 for gasoline or other light fuel to be used for engine starting and warm-up purposes.

Near the end of any period of operation of the engine by fuel oil supplied through the pipe 17, the supply of such oil is cut off and gasoline is admitted through the pipe 50 to the carburetor 12. The engine thus is conditioned for subsequent starting and warm-up by utilizing gasoline as fuel. After starting and warm-up of the en-

gine, the supply of gasoline to the carburetor 12 is cut off and the engine is operated by oil supplied to the carburetor through the pipe 17, the thermostat 19 together with the spring 29 serving to actuate the valve 14 to regulate flow of engine exhaust gases through the chamber 13 and thus maintain the fuel oil at a predetermined temperature best adapting it for use as fuel by the engine. At the same time, the thermostat 40 together with the spring 48 serves to actuate the valves 36 and 37 to regulate the supply of hot and cool air to the pipe 32, and thus maintain the air supplied through said pipe to the carburetor 12 at a predetermined temperature for intermixture with the oil at its predetermined temperature to afford the most efficient engine operating oil and air fuel mixture.

Separate valves may be employed to control flow of gasoline and fuel oil through the pipes 50 and 17 to the carburetor 12. Preferably, however, a single valve, such as the valve 18, is employed to establish communication between either of said pipes and the carburetor and simultaneously to deny communication between the other of said pipes and the carburetor.

The pipe 17 may be covered with suitable heat insulating material or may be jacketed, as indicated at 51, to minimize loss of heat from the fuel oil during its flow from the container 15 to the carburetor 12. Similarly, the carburetor itself may be jacketed or otherwise suitably insulated to prevent loss of heat from the oil while it is contained in said carburetor.

According to the Figs. 4 to 7 form of the invention, the construction and mode of operation of the apparatus is generally the same as described in connection with the Figs. 1 to 4 form of the invention, except that the engine manifold is made to serve the purpose of the jacket 30. Accordingly, it is deemed unnecessary to repeat the foregoing description of parts which are common to both forms of the invention. Instead the same reference characters, primed, are employed to designate in Figs. 5 to 7 parts corresponding to those previously referred to in the description of the Figs. 1 to 5 form of the invention.

As in the Figs. 1 to 4 form of the invention, the engine intake and exhaust manifolds 10' and 11', respectively, may be formed either separately from each other or as a single unit. In any event, the exhaust manifold 11' includes, as usual, a horizontal portion, designated as 11^a, a vertical portion, designated as 11^b, extending downwardly from the rear end of said horizontal portion, and a chamber 13' which is in communication with said horizontal and vertical portions through ducts 11^c and 11^d, respectively, under the control of a pivoted valve 14'. Moreover, said exhaust manifold is jacketed, as indicated at 52, to provide, exteriorly thereof, an air chamber 53 which is substantially coextensive in length with the portions 11^a and 11^b. Connected with this chamber is an atmospheric or cool air supply pipe 49' corresponding to the pipe 49 of the Figs. 1 to 4 form of the invention. Also connected with this chamber, at a point remote from the connection of the pipe 49' therewith, is a pipe 34' corresponding to the pipe 34 of the Figs. 1 to 4 form of the invention. Obviously, hot exhaust gases flowing through the exhaust manifold 11' serve to heat air in the chamber 53 prior to its delivery via the pipe 34' to the pipe 32'. In this connection and as illustrated in Fig. 7 of the drawings, the chamber 53 includes horizontal and vertical portions 53^a and 53^b which are substantially coextensive in length.

with the horizontal and vertical portions 11^a and 11^b, respectively, of the exhaust manifold 11' and has its horizontal portion 53^a divided by a longitudinally extending partition wall 54 into elongated, outer and inner passageways 55 and 56, respectively, which are closed with respect to each other at the rear end of the portion 53^a by said partition wall and are in communication with each other at the front end of said portion 53^a. Further in this connection and as illustrated in Fig. 7 of the drawings, the pipe 49' is connected to the outer passageway 55 near its rear or closed end, and the pipe 34' is connected to the vertical portion 53^b of the chamber 53 near the lower end of said vertical portion 53^b. Thus, air flowing from the pipe 49' to the pipe 34' is required to travel substantially the full length of the passageways 55 and 56 and substantially the full length of the vertical portion 53^b of the chamber 53 so as to be effectively heated by the exhaust gases.

In other respects and as aforesaid, the Figs. 5 to 7 form of the invention is generally the same in construction and mode of operation as the Figs. 1 to 4 form of the invention.

From the foregoing description considered in connection with the accompanying drawings, it is believed that the construction and mode of operation of the invention will be clearly understood and its advantages appreciated. It is desired to point out, however, that while only certain specific structural embodiments of the invention have been illustrated and described, the same is readily capable of specifically different structural embodiments within its spirit and scope as defined in the appended claims.

I claim:

1. An internal combustion engine manifold having an exhaust gas passageway including an elongated horizontal portion and a vertical portion extending downwardly from the rear end of said horizontal portion, said manifold further having a chamber at its rear end disposed rearwardly of the junction between said portions of said passageway to contain a portion of a fuel oil supply line, said manifold additionally having a pair of ducts one leading from the rear end of the horizontal portion of said passageway to the top of said chamber and the other leading from the bottom of said chamber to the downwardly extending portion of said passageway, a pivoted valve in said passageway at the junction of its horizontal and downwardly extending portions swingable to regulate flow of exhaust gases from said horizontal portion through said first mentioned duct into said chamber and effective when opened to deflect exhaust gases from said horizontal portion through said first mentioned duct

into said chamber, a jacket surrounding and substantially coextensive in length with the horizontal and the vertical portions of said exhaust gas passageway to provide an air chamber exteriorly of the said horizontal and vertical portions of said exhaust gas passageway, a partition wall within said air chamber dividing the same into outer and inner air passageways the former of which is substantially coextensive in length with the said horizontal portion of said exhaust gas passageway and the latter of which is substantially coextensive in length with the horizontal and the vertical portions of said exhaust gas passageway, means closing said air passageways with respect to each other at their rear ends, said air passageways being in communication with each other at their front ends, said outer air passageway having an air inlet opening at its rear end, and said inner air passageway having an air outlet opening adjacent to the bottom of its vertical portion.

2. An internal combustion engine manifold having a substantially horizontal exhaust gas passageway, said manifold further having a chamber at its rear end to contain a fuel oil supply line, said manifold additionally having a pair of ducts providing communication between said exhaust gas passageway and said chamber, a pivoted valve in said passageway between said duct swingable to regulate flow of exhaust gases through said ducts to and from said chamber from and to said passageway, a jacket surrounding and substantially coextensive in length with said exhaust gas passageway to provide an air chamber exteriorly thereof, a partition wall in said chamber extending longitudinally thereof and dividing the same into outer and inner air passageways closed at their rear ends and in communication with each other at their front ends, said jacket having an air inlet opening leading to the rear end of said outer air passageway and further having an air outlet opening leading from the rear end of said inner air passageway.
